Atty.

UNITED STATES PATENT OFFICE.

FRANK H. SWANSON, OF CHICAGO, ILLINOIS, ASSIGNOR TO A. J. NYSTROM AND COMPANY, A CORPORATION OF ILLINOIS.

MAP-CASE.

1,384,874.

Specification of Letters Patent. Patented July 19, 1921.

Application filed January 7, 1920. Serial No. 350,041.

To all whom it may concern:

Be it known that I, FRANK H. SWANSON, a citizen of the United States, residing at the city of Chicago, in the county of Cook and State of Illinois, have invented certain new and useful Improvements in Map-Cases, of which the following is a specification.

My invention relates to cases in which maps are suspended and stored and particularly to that class of cases which are attached to the wall of the room and in which a considerable number of maps mounted on separate rollers are secured for ready reference. In actual practice in this industry the maps are usually made of certain standard lengths while the trade demands cases which are adapted to receive such maps in greater or less numbers. To supply this demand it has been heretofore necessary to place cases in stock in such variety as to meet the probable demand; and as the demands cannot be accurately foreseen it is difficult to keep on hand a complete assortment of such cases.

It is the object of my invention to provide means by which, with a limited number of the component parts on hand, cases of any desired size, capacity or character may be supplied.

The materials therefor may be gathered together and shipped from stock on hand without assembly. This "knock-down" form permits compact shipping packages and practically does away with damage in transit. My improved construction fundamentally provides the materials for an open case, but may be adapted to include backs and doors as desired to form closed cases, the same being merely drawn from stock and included with the shipment. Upon receipt, all the component parts may be assembled without gluing or nailing, with the minimum of mechanical skill and without the possibility of mistake. When so assembled the cases are fully braced and of greater strength and lasting quality than similar cases made and secured together by ordinary cabinet making expedients. Means are also provided by which the cases may be attached to the wall at a proper angle, and by which when so attached they cannot be displaced except by deliberate intent.

The principles of my invention are illus-

trated in the drawings in which Figure 1, 55 shows a sectional elevation of my improved map case on the line 1, 1 of Fig. 2. Fig. 2 is an end view partly in section showing the same, secured in place for use. Fig. 3 illustrates the several parts in proper relation to each other for assembling. Fig. 4 is a detail of the suspending hook and attachment.

Further describing my invention with reference to the drawings in which like characters of reference denote like parts throughout: 1, 1 are the end or finishing pieces of the case. On the inner face, thereof, are bracing pieces 2, 2 which are slightly shorter than the finishing pieces to which they are attached by screws 3, 3 or other suitable means. One of the bracing pieces has holes 4 which are adapted to receive the stub shafts upon one end of a spring map or curtain roller. The bracing pieces at the other end of the case should be provided with a device to take the squared or flattened end of the spring shaft of such a roller. The device shown in the drawing is that set forth in my Patent No. 1,092,607 dated April 7, 1914. The finishing pieces are provided with grooves or recesses 6, which are adapted to receive the body portion 7 of L-bolts. The offset portion 8 of such bolts projects outwardly beyond the face of the finishing pieces and is adapted to be secured rigidly in place by a washer 9 and nut 10. A plurality of cap pieces 12 are adapted to provide the top and bottom respectively of the case when assembled. They are provided at points adjacent to the ends with gains or grooves 13 which receive the ends 14 of the finishing pieces 1, which project beyond the bracing pieces 2. The said grooves 13 are further provided with openings 15 to receive the extended ends of the L-bolts 7. And the said grooves should preferably be of a depth slightly greater than the extension of the end pieces 14 beyond the bracing pieces 2. It will be seen that when the parts shown in Fig. 3 are assembled and drawn rigidly into position by the nuts, on the L-bolts, the ends 2' of the bracing pieces will be brought into positive engagement with the inner faces of the cap pieces, insuring a rigid and practically indestructible structure.

A practical means for securing the case, described, to the wall or other support is

provided by the hook shown in detail in Fig. 4, which comprises a threaded body portion 20 and a nose 21 placed at a rather acute angle to each other preferably of about 5 forty-five degrees. A socket 22 should be securely embedded in the rear of the upright portions of the case, preferably in the bracing strip. A means is thus provided, by which the amount of extension given to the 10 hook may be adjustably varied. The extension should be such, that when suspending staples or eyes 23 are secured to a wall or other support, and the hooked end is put in proper relation to the opening in said eye, 15 the lower edge of the case at 24 will slide on the wall, while the part 21 will just enter the said opening. As the case descends, the hook will rest in proper position on the eye as shown in Fig. 2. When the parts are 20 assembled in the manner and in the relations described, the case can only be displaced from the support by an exact reversal of the process and accidental displacement in which the lower and rear portion 25 of the case is removed from the face of the support, will be impossible.

The foregoing construction and assembly represents a structure applicable to the use set forth which shall be open at all times; 30 but where it is desired to provide a closed case, a back, and door may also be applied. In order that the back may be received in proper position the cap pieces 12 should have longitudinal grooves or rabbets 12' 35 extended from end to end thereof closely adjacent to their rear edges. In like manner the bracing pieces 2 should have similar grooves or furrows 2'' so positioned that when the parts are assembled the rabbets 12' and 2'' will form a continuous depression 40 in the interior of the case. Within this depression when the case is assembled the edges of the back 25 are rigidly and securely received.

45 A door 30 by which the case may be completely closed is provided with hinges which comprise the leaf 31 attached to the lower edge of the door by screws 32, the strap 33 and the hook or pintle 34. The extended 50 rear leaf of the hinge 33 provides means by which it may be very strongly attached to the case by causing the projecting end of the lower L-bolt 7 to pass through a properly positioned hole in the strap. The leaf thus 55 acts as a washer to draw the parts of the device more rigidly together while they are being assembled as illustrated in Fig. 2 and replaces the washers which are shown in Fig. 1 which should be used where the open 60 form of the case is preferred.

I claim:

1. In a map case; the combination of upper and lower crown pieces having transverse gains adjacent to their ends, end pieces 65 having their ends adapted to enter said

gains, bracing pieces securely attached to the end pieces, and means for drawing the ends of the bracing pieces into rigid contact with said crown pieces.

2. In a map case; the combination of upper and lower crown pieces having transverse gains adjacent to their ends, end pieces having their ends adapted to enter said gains, bracing pieces securely attached to the end pieces, and means for drawing the ends of the bracing pieces into rigid contact with said crown pieces, the ends of said end pieces remaining out of contact with the bottoms of the said gains.

3. In a map case; the combination of upper and lower crown pieces having transverse gains adjacent to their ends, end pieces having their ends adapted to enter said gains, bracing pieces securely attached to the end pieces, and L-bolts having their ends 85 projecting beyond the faces of the finishing and crown pieces at each corner of the case to draw the proximate parts thereof into rigid relation to each other.

4. In a map case; the combination of upper and lower crown pieces, end pieces having their ends adapted to adjustable engagement with the crown pieces, bracing pieces securely attached to the end pieces, said crown and bracing pieces being provided 95 with rabbets adjacent to their rear edges to form a continuous groove within the case, a back having its edges received within the groove, and means for drawing the ends of the bracing pieces into rigid contact with 100 said crown pieces.

5. In a map case; the combination of upper and lower crown pieces, end pieces having their ends adapted to adjustable engagement with the crown pieces, bracing pieces 105 securely attached to the end pieces bolts connected with the bracing pieces for drawing their ends into rigid contact with the crown pieces, a back for the said case and a door hinged to the front thereof.

6. In a map case; the combination of upper and lower crown pieces, end pieces having their ends adapted to adjustable engagement with the crown pieces, bracing pieces securely attached to the end pieces bolts 115 connected with the bracing pieces for drawing their ends into rigid contact with the crown pieces, a back for the said case and a door having its hinges secured to said case by said bolts.

7. In a map case; the combination of upper and lower crown pieces, finishing pieces having their ends adapted to adjustable engagement with the crown pieces, bracing pieces securely attached to the end pieces, 125 having their ends projecting beyond the faces of the finishing and crown pieces at each corner of the case to draw the proximate parts into rigid relation to each other, a back for said case, and a door having its 130

hinges secured to said case by the bolts projecting from one of the crown pieces.

8. In a map case; the combination of upper and lower crown pieces having transverse gains adjacent to their ends, finishing pieces having their ends adapted to enter said gains, bracing pieces securely attached to the end pieces, L-bolts having their ends projecting beyond the faces of the finishing and crown pieces at each corner of the case

to draw the proximate parts into rigid relation to each other, a back for said case, and a door having its hinges secured to said case by the L-bolts projecting from one of the crown pieces.

In witness whereof I have hereto set my hand at Chicago, Illinois, this 30th day of December, 1919.

15

FRANK H. SWANSON.
